UNITED STATES PATENT OFFICE.

WILLIAM F. WEGNER, OF NEW YORK, N. Y., ASSIGNOR TO STEPHEN T. WILLIAMS, OF NEW YORK, N. Y.

INCANDESCENT-LAMP SOCKET.

No. 897,805.

Specification of Letters Patent.

Patented Sept. 1, 1908.

Application filed August 26, 1907. Serial No. 399,393.

To all whom it may concern:

Be it known that I, WILLIAM F. WEGNER, a citizen of the United States, and resident of the borough of Manhattan, in the city and 5 State of New York, have invented a new and useful Incandescent-Lamp Socket, of which the following is a specification.

My invention relates to an incandescent lamp socket, with the object in view of providing a simple and effective socket capable 10 of receiving the globe or glass bulb without the necessity of screwing it to its position and at the same time capable of holding the bulb securely in position against displacement except by an unscrewing action.

A practical embodiment of my invention is represented in the accompanying drawings, in which

Figure 1 is a top plan view of the socket 20 with the bulb in position, Fig. 2 is a similar view with the bulb and protecting ring removed, Fig. 3 is a bottom plan view of the protecting ring, Fig. 4 is a view of the socket in side elevation with the bulb in position, 25 Fig. 5 is a vertical section in the plane of the line A—A of Fig. 1, Fig. 6 is a bottom plan view, and Fig. 7 is a horizontal section in the plane of the line B—B of Fig. 4.

The body of the socket is denoted by 1. 30 It is provided with an upwardly extending tubular portion 2 for the reception of the lower screw threaded end of the glass bulb 3. The interior screw thread 4 in the tubular extension 2 is of ratchet formation to permit 35 the bulb to be slid downwardly into position without rotating it and the interior of the tubular extension 2 is sufficiently large to permit this direct insertion of the bulb. A contact piece 5 extends upwardly within the tubular extension 2 and is screw threaded or 40 bent into screw thread shape to correspond to the thread 4, the piece 5 being of spring metal and normally set to press the lower end of the bulb 3 against the wall of the tubular extension 2.

The contact piece 5 is held in position by extending its tail 6 outwardly through the wall of the upward extension 2 and over a marginal shoulder 7 on the body 1 and is held 45 in position by means of a screw 8 passing through the body 1 into the piece 5, the head of the screw 8 being received in a socket 9 formed in the body 1. A binding post 10 is screwed into the tail 6 of the contact piece 5 for holding the conducting wire in position,

the shoulder 7 on the body 1 being recessed as shown at 11, 12, for the reception of the wire. A second contact piece 13 extends from a position to engage the inner end of the bulb 3 outwardly through the wall of the tubular extension 2 over the shoulder 7 on the body 1, preferably in a direction opposite that in which the tail 6 of the contact piece 5 extends, the piece 13 being held in position by a screw 14 in a manner quite similar to 60 that in which the screw 8 holds the piece 5 in position. The contact piece 13 is also provided opposite the shoulder 7 with a binding post 15 and the shoulder 7 is recessed as shown at 16, 17, Fig. 2, for the accommodation 65 of the conducting wire leading to the binding post 15.

The contact piece 13 is of spring metal and normally occupies a position in the path of the bulb 3 as it is projected inwardly so as to 70 insure a close and effective contact when the bulb 3 is seated. The binding posts 10 and 15 as well as the wires in proximity thereto are completely protected by a suitable covering ring 18 of insulating material which fits 75 around the tubular extension 2 and over the shoulder 7 on the body 1, the under side of the ring 18 being recessed at 19, 20, to accommodate binding posts and also provided with recesses corresponding to the recesses 80 11, 12, 16, 17, in the body 1 for the reception of the wires. The covering ring 18 may be held in position by screws 21, 22, which screws may also serve to hold the socket in position by extending them into the socket 85 support as shown in Fig. 4. It is to be understood that the body 1 of the socket and its tubular extension 4 are to be made of some suitable insulating material, as, for example, porcelain, hard rubber, etc.

In operation, the bulb 3 may be placed in position by pressing it directly toward the contact piece 13, the contact piece 5 springing backwardly to permit the screw threads on the bulb to ride over those on the contact 95 piece 5 and on the inner face of the tubular extension 2 and when the bulb has reached the contact piece 13 it may be given a partial turn, if necessary, to press it more tightly into engagement with the contact piece 13. 100 The bulb will be held by the ratchet shape of the screw thread securely in its position when once adjusted and may be removed if required by unscrewing it as is usual. This feature of rapidly inserting the bulb is of 105 110

great importance where bulbs are used by the thousand as in the electrical displays and electrical lighting now common, while the socket as a whole protects the contact pieces and wires from exposure and forms an effective electrical contact between the bulb and conducting wires.

What I claim is:—

1. A lamp socket provided with a screw threaded portion of greater diameter than the diameter of the screw threaded end of the lamp bulb to be inserted therein and capable of receiving the screw threaded end of the lamp bulb by a direct thrust and a yielding contact piece, arranged along the side wall of the socket for holding the bulb in position in the socket.
2. The combination with a lamp socket and a lamp bulb provided with a screw threaded end, the socket being provided with a screw threaded opening of greater diameter than the diameter of the screw threaded end of the lamp bulb and capable of receiving the screw threaded end of the lamp bulb by a direct thrust, of a spring contact piece arranged between the side wall of the socket and the bulb, to engage the screw threaded end of the bulb within the socket.
3. The combination with a lamp socket, and a lamp bulb, the socket having a portion of its wall constructed to yield to permit the entering of the lamp bulb by direct thrust and provided with a screw threaded interior for retaining the bulb in position.
4. An electric lamp socket provided with a tubular extension and an annular shoulder around the tubular extension, the said tubular extension being provided with a ratchet

shaped screw thread, a yielding contact piece having its face formed to correspond to the screw thread on the interior of the tubular extension, the said contact piece extending along the inner wall of the extension, the relation of the said contact piece to the opposite wall of the tubular extension being such that a lamp bulb may be inserted between the contact piece and the wall of the tubular extension only by crowding back the contact piece.

5. An electric lamp socket comprising a body portion provided with a tubular extension and an annular shoulder, the tubular extension being provided with an interior screw thread, a spring contact piece extending along and spaced from the inner wall of the tubular extension and extending thence through the tubular extension onto the said annular shoulder, a second contact piece extending from the interior tubular extension through the wall thereof onto the annular shoulder, fastening devices extending through the body of the socket into engagement with the contact pieces, binding posts engaged with the contact pieces opposite the annular shoulder and a protecting ring surrounding the tubular extension and concealing the binding posts.

In testimony, that I claim the foregoing as my invention, I have signed my name in presence of two witnesses, this sixteenth day of August, 1907.

WILLIAM F. WEGNER.
